G. ARTUS,
AUTOMATIC GASOLENE AND OIL VENDER,
APPLICATION FILED NOV. 29, 1915.

1,255,812.

Patented Feb. 5, 1918.

UNITED STATES PATENT OFFICE.

GEORGE ARTUS, OF CLEAR LAKE, SOUTH DAKOTA, ASSIGNOR TO WORTHINGTON MANUFACTURING COMPANY, OF WORTHINGTON, MINNESOTA, A CORPORATION.

AUTOMATIC GASOLENE AND OIL VENDER.

1,255,812.

Specification of Letters Patent

Patented Feb. 5, 1918.

Application filed November 29, 1915. Serial No. 84,090.

To all whom it may concern:

Be it known that I, GEORGE ARTUS, a citizen of the United States, residing at Clear Lake, in the county of Deuel and State of South Dakota, have invented certain new and useful Improvements in Automatic Gasolene and Oil Venders, of which the following is a specification.

This invention relates to vending machines for dispensing liquids automatically in a measured amount corresponding to the denomination of the coin inserted.

The main objects of my invention are to provide an apparatus dispensing liquids of different grades which can be predetermined by the purchaser and in varying amounts automatically controlled by the denomination of the inserted coin.

The invention will be understood from the following detailed description in connection with the accompanying drawings, in which Figure 1 is a diagrammatic view of an apparatus embodying my invention; and Fig. 2 is a detail view of a modified form of one of the parts.

For the purposes of clearness I have not shown the supporting framework. A suitable number of coin chutes 1 graduated in size to receive coins of different denominations are provided which lead to the shallow grooves 2, 2^a, etc., in the coin-cylinder 4, these grooves being a depth to permit the coin to project beyond the periphery of the cylinder. Corresponding with the grooves and in a position to be engaged by the coins when the cylinder 4 is rotated, are a series of swinging levers 6, 6^a, pivoted at their upper ends 6^b. A coin in one of the grooves will engage one lever or the other, pushing it away from the cylinder, and acting through the links 8, 8, rotates the bell-crank lever 9, 10, 12, upon its pintle 14, and causing the dog 15, carried by the arm 12, to swing the weighted inverted pendulum 17, forward upon the horizontal pivot 18. As the dog 15, slips off the side of the pendulum rod 16, the spring 19, causes the pendulum to fly back with sufficient force to strike a hammer blow upon the lug 20, thereby rotating the switch 21 and causing the blade 23 to engage the contact 24, thus closing the circuit of the electric motor 25, connected to the pump 26. This movement of the switch, acts through the link 28, to

lift the arm 30, pivoted at 31, and which will return the switch to "off" position when it is engaged by one of the stop lugs 32, 33, 35 or 36, in a manner hereinafter described.

When the pump 26 is driven by the motor, the gasolene or other liquid will be pumped from the main supply pipe 55 through the pipe 38, into the dispensing tank 40. As the tank is being filled the float 42, rises and causes the cable 43 to gradually lower the cross-head 45, carrying the stop rods 46, 47, until one of the stop-lugs strikes the arm 30, causing it to descend and swing the switch 21 to the "off" position with the blade 23 resting upon a back-stop 22, thereby breaking the circuit and stopping the motor.

I have shown four stop lugs which are adjustable on the rods 46, 47 and are arranged at different elevations corresponding with different quantities of liquid that will be pumped into the tank when the motor operates for corresponding periods of time. These stops may be set to different points on the rods in accordance with the fluctuations in the market price of the gasolene, oil or other liquid. The rods 46, 47, are freely slideable in the guides 50, 51, and are suspended from the block or cross-head 45, carried by the swivel 49 on the end of the cable 43.

The pump may be connected to either supply pipes 56, or 57 so that different grades of oil may be supplied. This may be controlled by rocking the control lever 60, either to the right or to the left, thereby swinging the valve 61, to open communication with one supply pipe or the other. Then by pushing the lever forward the link 62, and arm 63 will turn the guide 51 causing the block 45 to turn on the turnbuckle 49 as a pivot and bring the rod 46 adjacent the lever 30 so that the stops 32 and 33 will be in alinement therewith. By pulling the control lever 60 in the opposite direction, the link 62 will swing the block 51 in the reverse direction to thereby oscillate the block 45 on the pivot 49, bringing the rod 47 adjacent the lever 30 and the stops 35, 36 in alinement therewith. These preliminary lateral and forward or backward movements of the control lever 60, determine the grade of liquid to be pumped and the set of quantity stops brought in alinement with the

motor-stopping lever 30, the particular stop to be engaged being determined by the denomination of the coin inserted.

I have previously described the manner in which the insertion of a coin in any slot will cause the actuation of the pendulum 17 to throw the switch 21 and thereby close the circuit through the motor 25. The manner in which the different coins determine the particular stop that shall engage the lever 30 is as follows:—If a coin is inserted in slot 2, the lever 6 will be engaged by the coin when the cylinder 4 is rotated by the handle 7, pushing the lever back and causing the bar 11 to oscillate in a clockwise direction upon its pintle 13, thereby swinging the arm 30, in a clockwise direction and causing the bell-crank 71 to move on its pivot 72 in a direction to push the link 74 and guide 50 forwardly. The rod 46 will thus be swung toward the arm 30, causing the lower, shorter stop 32 to be in direct vertical alinement with said arm. Under these conditions, the float 42 in the tank can only rise until the cable 43 descends sufficiently to cause the lower stop 32 to strike the arm 30 and lower it sufficiently to open the switch 21 thus breaking the motor circuit.

If, however, the proper coin is inserted in the slot 2^a, the rotation of the cylinder 4 will cause the lever 6^a to swing backward, thereby oscillating the bar 11 in an anti-clockwise direction and causing the bell-crank 71 to pull the guide 50 backward. This movement swings the rod 46 away from the arm 30 sufficiently to move the lower stop 32 out of alinement with the arm 30 but leaving the longer upper stop 33, still projecting thereover. Consequently the motor will continue to operate until the float has risen to a higher level, sufficient to permit the descending stop 33, to engage the lever 30, to open the switch 21 in the manner described. I have deemed it sufficient for purposes of illustration to show two coin slots and the mechanism controlled thereby to determine the period of operation of the motor driven pump, but it is obvious that I may provide any desired number of coin slots with a corresponding number of coöperating elements to effect the proper movement of the stops.

Instead of placing the arm 30 at one side of the stop rods, I may place it between the rods; and I may also place all of the stops upon one bar 46' as shown, for instance, in Fig. 2, the bar being turned axially by the lever 60 in substantially the manner previously described.

The valve 75, in the outlet pipe 76, connecting with the hose 78, may be normally open and be automatically maintained closed while the tank is being filled in any suitable manner, as for instance by connection with

the float or with an operating part of the pump. I have shown the valve controlled by suitable lever mechanism 80, with a centrifugal governor 81, on the shaft of the pump. When the pump is in operation the valve will be maintained closed, and will be opened when it stops, permitting the contents of the tank to flow out through the hose 78 and nozzle 79.

The operation of my liquid vender will be understood from the foregoing detailed description. When oil or other liquid of different grades is supplied, the particular grade or quality is determined by the lateral movement of the control lever 60, and the set of quantity stops covering the range of prices which include the coin which is to be deposited is determined by the forward or backward movement of the said control lever 60. A coin being deposited in one of the coin slots, the crank 7 is turned to oscillate the cylinder 4, thereby bringing the projecting rim of the coin into engagement with one of the swinging levers 6 or 6^a. The movement of either arm operates through the links 8, bell-crank 9, 10, 12 and dog 15 to swing the pendulum 17, and cause it to rebound with a hammer blow upon the lug 20, causing the switch arm 23 to close the circuit of the motor 25 to thereby actuate the pump 26. The particular denomination of the coin deposited controls the direction of movement of the bar 11, and the consequent swinging movement of the rods 46, 47 which determines the particular stop lug that shall engage the arm 30, to open the motor switch when the tank float has risen sufficiently to lower said stop. Upon the stoppage of the motor and pump the valve 75 automatically opens to discharge the contents of the tank.

I have particularly described the mechanism illustrated in the accompanying drawings for the express purpose of clearly disclosing an embodiment of my invention but I am aware that various changes and modifications can be made within the scope of my claims and without in any manner departing from the scope of my invention.

I claim:—

1. A vending machine, comprising a dispensing tank or receptacle, an outlet valve therefor, a pump to supply a liquid to said tank, driving mechanism for the pump, coin-controlled means governing the operation of said driving mechanism, means controlled by the elevation of the liquid in the tank for stopping said mechanism, and means controlled by the operation of said driving mechanism holding said outlet valve closed only during the filling operation.

2. A vending machine, comprising a dispensing tank or receptacle, an outlet valve therefor, a pump to supply a liquid to said tank, driving mechanism for the pump, 130

means controlling the power supplied to said mechanism, a plurality of stop devices under the control of the liquid in the tank for shutting off said power, and coin-controlled

5 means for causing one or another of said stop devices to be effective.

3. A vending machine, comprising a dispensing tank or receptacle, an outlet valve therefor, a pump to supply a liquid to said

10 tank, driving mechanism for the pump, means controlling the power supplied to said mechanism, a plurality of stop devices under the control of the liquid in the tank for shutting off said power, and coin-controlled

15 means actuating the power controlling means and for causing one or another of said stop devices to be effective.

4. A vending machine, comprising a dispensing tank or receptacle, a pump to sup-

20 ply liquid to said tank, driving mechanism for the pump, means controlling the power supplied to said mechanism, a stopping device for said mechanism, a plurality of sets of stops under the control of the liquid in

25 the tank adapted to actuate said stopping device, means for moving a single set of stops into operative position, and coin-con-

trolled means for causing one or another stop of said selected set to be effective.

30 5. A vending machine, comprising a dispensing tank or receptacle, a pump to supply liquid to said tank, driving mechanism for the pump, means controlling the power supplied to said mechanism, a stopping de-

35 vice for said mechanism, a plurality of sets of stops under the control of the liquid in the tank adapted to actuate said stopping device, means for moving a single set of stops into operative position, and coin-con-

40 trolled means for actuating the power controlling means and for causing one or another stop of said selected set to be effective.

6. A vending machine, comprising a dispensing tank or receptacle, a plurality of

45 sources of liquid supply, a pump to supply

liquid to said tank, means to connect one or another of said sources to said pump, driving mechanism for the pump, means controlling the power supplied to said mechanism, a stopping device for said mechanism, a plu- 50 rality of sets of stops, under the control of the liquid in the tank adapted to actuate said stopping device, means for moving a single set of stops into operative position, and coin-controlled means for causing one or another 55 stop of said selected set to be effective.

7. A vending machine, comprising a dispensing tank or receptacle, a pump to supply liquid to said tank, motor actuating mechanism for the said pump, coin controlled 60 means for governing the starting of said actuating mechanism and said means being also influenced by the dimensions of the coin for predetermining the time duration be- 65

tween starting and stopping the pump.

8. A vending machine, comprising a dispensing tank or receptacle, a pump to supply liquid to said tank, operating mechanism for said pump, coin controlled starting and stop- 70 ping devices for said mechanism and pump, means controlled by the coin for predeter- mining the duration of operation of said pump, and means for adjusting the stopping device for said pump, independent of the coin controlled device.

9. A vending machine, comprising a dispensing tank or receptacle, a plurality of sources of liquid supply, a pump to supply liquid to said tank, means to connect one or another of said sources to said pump, coin 80 controlled starting and stopping devices for the said pump, and means controlled by the coin for predetermining the time limit of operation of said pump.

In testimony whereof I affix my signature 85 in presence of two witnesses.

GEORGE ARTUS.
